UNITED STATES PATENT OFFICE.

JOHN D. HOFFMAN, OF STRATFORD, ONTARIO, CANADA.

PEAT DRIER.

Application filed March 3, 1922. Serial No. 540,786.

To all whom it may concern:

Be it known that I, JOHN D. HOFFMAN, a subject of the King of Great Britain, residing at Stratford, in the Province of Ontario and Dominion of Canada, have invented new and useful Improvements in Peat Driers, of which the following is a specification.

This invention relates to an apparatus and 10 a process for drying peat, the general object of the invention being to cause the peat to pass through a stream of hot air, the peat moving in one direction and the air in an opposite direction.

15 Another object of the invention is to provide means for retarding the passage of peat through the air and to agitate and divide the same so that the air will thoroughly contact with the peat.

20 This invention also consists in certain other features of construction and in the combination and arrangement of the several parts, to be hereinafter fully described, illustrated in the accompanying drawings 25 and specifically pointed out in the appended claim.

In describing my invention in detail, reference will be had to the accompanying drawings wherein like characters denote like 30 or corresponding parts throughout the several views, and in which:—

Figure 1 is an elevation of the invention.

Figure 2 is a fragmentary sectional view 35 showing the means for supplying hot air to the peat.

Figure 3 is a section on line 3—3 of Figure 2.

Figure 4 is an enlarged view showing a portion of one side of one of the stacks.

40 Figure 5 is a section on line 5—5 of Figure 4.

Figure 6 is a section on line 6—6 of Figure 2.

Figure 7 is a fragmentary view showing 45 the means for rotating the agitators.

In these views 1 indicates a stack into the upper end of which the peat is delivered by the conveyor 2 which receives the peat from the crusher 3. A stream of hot 50 air is introduced into the lower part of the stack by means of the pipe 4 which may be connected with any suitable source of supply. Figure 2 shows this pipe as being connected with a blower 5 which has its inlet 55 pipe 6 passing through a furnace 7 so that the air entering the blower will be heated.

It will of course be understood that any desired means may be provided for supplying hot air to the stack. A substantially V-shaped deflector 8 is placed in the stack 60 above the outlet of pipe 4 so as to deflect the same towards the sides of the stack. The peat dropping from the upper end of the conveyor will fall upon the agitators 9, 65 which are arranged on the shafts 10, journaled in the stack. These shafts are arranged in parallel pairs, the shafts having gear wheels 11 on their projecting ends which mesh with each other. One of the lower shafts is provided with a pulley 12 70 which may be belted to any suitable source of power for rotating the shafts and the agitators thereon. The shafts of each pair rotate in opposite directions and each alternate pair rotate in a reverse direction from 75 the adjacent pairs. The agitators consist of pronged members and the agitators on the shaft of one pair are alternately arranged with those on the other shaft of the pair. These agitators will break up the peat into 80 small particles and will agitate the same and at the same time retard its passage down the stack, thus giving the hot air a chance to come in contact with all portions of the peat and thus drying the same. If the 85 passage down one stack is not sufficient to dry the peat a second stack 1' may be provided, as shown in Figure 1, the peat being carried from the bottom of the first stack 90 to the top of the second stack by the conveyor 2'. Of course any number of stacks may be provided to insure the drying of the peat.

From the above it will be seen that the slow passage of the peat down the stack, 95 due to the action of gravity, will subject the same to the action of the stream of air passing up the stack and thus cause the air to dry the peat.

In order to permit the agitators and their 100 shafts to be inspected or repaired I form one side of the stack of a plurality of plates 13 which carry the bearings for the projecting portions of the shafts and which are bolted in place as shown at 14. By this 105 means a few of the shafts and agitators can be removed without removing the entire number.

It is thought from the foregoing description that the advantages and novel features 110 of my invention will be readily apparent.

I desire it to be understood that I may

make changes in the construction and in the combination and arrangement of the several parts, provided that such changes fall within the scope of the appended claim.

5 What I claim is:—

An apparatus for drying peat comprising a plurality of stacks, a substantially V-shaped deflector transversing each stack adjacent the bottom thereof, means for forcibly introducing heated air into each stack below the deflector, a plurality of plates arranged in edge to edge relation and forming one side wall of each stack whereby access may be readily had to the interior

thereof, a plurality of shafts arranged in parallel pairs and finding bearings in the side walls of each stack, gear wheels secured to all of the shafts and meshing with each other in a manner so as to rotate each alternative pair in opposite direction and each of the other pairs in reverse direction, an agitator secured to each shaft and being adapted to break up the peat and at the same time retard its passage down the stack and means for conveying peat from the bottom of one stack to the top of the other.

In testimony whereof I affix my signature.
JOHN D. HOFFMAN.
